UNITED STATES PATENT OFFICE.

WILLIAM HERSKOVITZ, OF CHICAGO, ILLINOIS.

SWITCH MECHANISM.

1,089,051.

Specification of Letters Patent.

Patented Mar. 3, 1914.

Application filed January 9, 1913. Serial No. 740,921.

To all whom it may concern:

Be it known that I, WILLIAM HERSKOVITZ, a citizen of the United States, residing at Chicago, in the county of Cook and State of Illinois, have invented a new and useful Improvement in Switch Mechanism, of which the following is a specification.

My invention relates to switch mechanism and particularly to chain-pull switch mechanism which may be used to great advantage in electric lamp sockets.

The object of the invention is to provide simpler and less expensive construction and arrangement and more efficient operation.

15 The various features of the invention are clearly illustrated in the accompanying drawings in which,

Figure 1 is a top view of an electric lamp socket, the shell being removed, Fig. 2 is a 20 side elevational view with the shell in vertical cross section, Fig. 3 is a view looking at Fig. 2 from the left, the shell being removed, Fig. 4 is a plan view looking from plane 4—4 Fig. 2, Fig. 5 is a plan view taken 25 on plane 5—5, Fig. 2, Fig. 6 is a plan view taken on plane 6—6, Fig. 2, Fig. 7 is a sectional view taken on plane 7—7, Fig. 1, the ratchet wheel being in section on plane 7—7, Fig. 5, Fig. 8 is a sectional view of the 30 ratchet wheel taken on plane 8—8, Fig. 5, and Fig. 9 is a sectional view of the ratchet wheel taken on plane 9—9, Fig. 5.

The various operating switch parts are arranged in the space between the upper 35 and lower supporting blocks 10 and 11 spaced and held apart by plates 12 and 13. The threaded shell 14 for receiving a lamp or socket extends from the lower block 11 and is held thereto by screws 15 and 16. 40 passing through the block and threading to plate 12 and nut 17 respectively, the plate being the circuit terminal for the shell and carrying clamping screw 18. The tip terminal 19 of the socket is in the form of a V shaped spring secured by one limb to the base of block 11 by screw 20. The screw extends through and engages with its head against the bottom of a metallic cylindric cup 21 sunk into block 11, this cup being 45 connected with switch spring 22 by a metal plate 23. As shown, this plate may be integral with the cup, and an intermediate section 23' thereof bent back a distance against itself and the end deflected upwardly and laterally to form the spring terminal 22. A screw 24 secures the outer end of the plate

to block 11. Directly above plate 23, the upper block 10 carries a circuit terminal 25 which has binding screw 26. From this terminal 25 the upper switch spring 27 extends and terminates vertically above the end of lower switch spring 22. The leads from a current supply circuit are connected to the circuit terminals 12 and 25 by binding screws 18 and 26 respectively, terminal 12 connecting permanently with the sleeve 14 while the other terminal depends for its connection with the tip spring 19 on the electrical connection of the switch springs 22 and 27.

The electrical connection of the switch springs is controlled by a disk 28 rotatable on the pivot pin 29. The disk is of insulating material and extending therethrough at diametrically opposite sides are metallic 75 switch plates 30 and 31. Whenever either plate comes between the switch springs, such springs are electrically connected and the socket tip terminal 19 will be connected with the supply circuit. At all other points 80 the insulation body of the disk will be between the springs to electrically disconnect them. The lower end of pin 29 extends into cup 21 while at its upper end its head 32 extends into pocket 33 in the upper block 10. 85 Segmental plates 34 and 35 are pivoted at their apexes on the pin respectively above and below the switch disk 28 and are spaced and held apart at their outer edges by posts 36. Between the plates and the disk washers 37 and 38 are inserted on the pivot pin. The lower plate 35 bears on a washer 39 encircling the projecting end of the cup 21 into which the pin extends. The plates connected by the posts form a ratchet pawl carrying structure, the pawl 40 being pivoted on the post 41 extending between the plates. This pawl cooperates with the ratchet teeth 28' on switch disk 28, there being four such teeth equally spaced apart. The pawl may, 90 as shown, be of sheet metal and provided with the pivot loop 40' at an intermediate point to receive the pivot post 41. The tail 40" of the pawl is bifurcated to receive and confine the end bead of the pull chain 42, 95 this chain passing out through the flared guide thimble 13' forming part of the plate 13 as clearly shown.

The chain passes in front of the pawl pivot post and the pawl body and when 110 the chain is pulled the pawl tail is swung out and the pawl point is forced against

the periphery of the switch disk to engage with a ratchet tooth and to thus cause the disk to rotate with the pawl supporting structure. To restore the pawl supporting structure a spring 43 is provided and encircles the pin 29 between upper plate 34 and the head 32 of the pin. The upper end of the spring is secured to the head by passing through a hole 32' therethrough, while the lower end abuts against post 44 on plate 34. The head 32 is polygonal as is likewise the pocket 33, and the spring by pressing against the head and pawl supporting structure, tends to hold this structure seated against washer 39 and to hold the head in the pocket to prevent turning of the pin. Below pocket 33 is a pocket 45 which is larger than the head so that if the head is pushed down out of the polygonal pocket it may be turned to adjust the tension of the spring, and when the head again enters the polygonal pocket the adjustment will be maintained. The cup 21 is of sufficient depth to allow the pin to be pushed down to release its head. The head has preferably a slot 32'' so that a screw driver may be used to effect adjustment. When the chain is released the pawl frame is swung back, the terminal 25 forming an abutment therefor. During such restoring movement of the pawl frame the switch disk remains at rest. This is caused by the clamping action of the switch springs on the disk body or on the switch plates 30 and 31. As clearly shown, each switch plate has top and bottom notches 30' and 31' in which the respective switch springs engage when the pawl frame has been swung to carry the switch disk outwardly. As each full outward swing of the pawl frame effects at least a 90 degree rotation of the switch disk, notches 46 and 46' are provided in the disk body on a diametral line at right angles with the line of the switch plate notches. The switch disk is therefore, after each 90 degree rotation locked by the engagement of the switch springs in either

the notches 30', 31' or the notches 46, 46', the switch disk alternately effecting electrical connection and disconnection of the switch springs. If the chain is pulled only partway out and then released, the pawl frame will be restored by the spring 43 while the switch disk will be held by the frictional engagement therewith of the switch springs in the position into which it was set by the partway outward movement of the pawl frame. As soon as the pawl frame is then swung fully outwardly a set of locking notches will receive the switch springs.

The structure thus far described is incased in a shell body 47 and cap 48 in a well known manner, an insulating lining 49 being also provided. The cap has the inlet 50 for current supply leads.

It is evident that the switch mechanism described may be used with equal advantage in other electrical circuit controlling devices and I do not therefore desire to be limited to the exact structure and application shown and described, except as such limitations appear specifically in the appended claim which is the following:

In electrical switch mechanism, the combination of a ratchet disk, a pawl frame, a pawl pivoted intermediate its ends to said frame, a pull chain connected with the tail of said pawl at one side of its pivot and passing over the pivot and against the end of said pawl at the opposite side of its pivot, and a guide for the chain situated to hold the chain against the pawl whereby upon pull on said chain the pawl will be rotated and its end firmly held to said ratchet disk and said disk rotated.

In witness whereof I have signed my name to the foregoing specification in the presence of two subscribing witnesses.

WILLIAM HERSKOVITZ.
